Primary Examiner — Robert M Spear*Assistant Examiner* — Marissa J Cash(74) *Attorney, Agent, or Firm* — Fulwider Patton LLP;
Gary M. Anderson(57) **CLAIM**

The ornamental design for a toy airship, as shown and described.

DESCRIPTION

FIG. 1 is a front perspective view of a toy airship unit showing my new design;

FIG. 2 is a rear perspective view thereof;

FIG. 3 is a right side elevational view thereof;

FIG. 4 is a left side elevational view thereof;

FIG. 5 is a top plan view thereof;

FIG. 6 is a bottom plan view thereof;

FIG. 7 is a front elevational view thereof; and,

FIG. 8 is a rear elevational view of my new design.

The features shown in broken lines illustrate environment of the toy airship that form no part of the claimed design.

1 Claim, 8 Drawing Sheets(56)
